UNITED STATES PATENT OFFICE.

RUDOLPH HOFFMAN, OF KANKAKEE, ILLINOIS, ASSIGNOR TO SEARS, ROEBUCK AND CO., OF CHICAGO, ILLINOIS, A CORPORATION OF NEW YORK.

OIL STOVE.

Application filed October 12, 1922. Serial No. 593,942.

To all whom it may concern:

Be it known that I, RUDOLPH HOFFMAN, a citizen of the United States, residing at Kankakee, in the county of Kankakee and 5 State of Illinois, have invented a certain new and useful Oil Stove, of which the following is a specification.

The invention relates to an oil stove of the type embodying a plurality of wickless burners which are controlled by raising and lowering them with respect to an oil supply maintained at a constant level.

The object of my invention is to provide an effectual means for thus raising and 15 lowering the burners of the oil stove, in combination with means for guiding the burners in their movements so as to maintain them at all times in a true horizontal position.

The object of the invention thus stated, 20 together with other and ancillary advantages, is attained by the construction and arrangement illustrated in the accompanying drawings forming part hereof in which Figure 1 is a fragmentary front elevational view of a burner equipped with my improved raising and lowering means. Fig. 2 is a fragmentary side elevational view of said means. Fig. 3 is a diagrammatic view illustrating a detail of construction. Fig. 4 is a fragmentary transverse sectional view 25 through the burner and its raising and lowering means and illustrating the connection between the burner and the source of oil supply permitting of the up and down movements of the burner. Fig. 5 is a fragmentary horizontal sectional view taken substantially in the plane of line 5 of Fig. 4.

It will be observed that one embodiment only of the invention has been illustrated 30 but it is contemplated that various changes in the form, construction and arrangement of the parts may be made by those skilled in the art without departing from the spirit and scope of the invention as expressed in 45 the appended claims.

The burner proper may be of any suitable or preferred construction. Herein I have shown it as comprising a burner bowl 7 which is commonly made annular in form 50 and upon which is supported a chimney or drum 8 for conducting heat produced by the burner to a grid supported in the top frame 9. The burner bowl is connected with a source of oil supply by means of a depending pipe 10 connected by means of a flexible 55

tube 11 with a supply pipe 12. The latter communicates by means of a pipe 13 with an oil well 14 which receives its supply of oil from a reservoir 15, the well and reservoir being supported at one end of the stove and 60 being in valve-controlled communication in a manner not herein shown but well known in the art, for the purpose of maintaining a constant oil level with respect to which the burner bowl may be raised and lowered to 65 control the flame.

The connection between the pipe 10 and the flexible tube 11 is effected by means of an elbow coupling 16, and the tube 14 is connected to the supply pipe 12 by means of a 70 fitting 17 in any suitable way, the latter being preferably detachably secured to the pipe 12 by means of a clamp device 18. 19 designates pairs of fingers mounted upon opposite sides of the tube 11 for the purpose 75 of distributing the bending strain over a substantial length of the tube 11. This tube consists of a plurality of relatively movable sections which render it flexible. For a detailed description of the tube and its associated parts, including the clamp 18, reference is made to my copending application Serial No. 540,744 filed March 3, 1922.

One of the essentials for the efficient operation of burners of this character is 85 that the burner bowls be maintained in a true horizontal position as they are raised and lowered, the reason for this being obvious,—that if the burner bowl is inclined the oil therein will not be distributed uniformly and hence the flame produced will be higher upon the side containing the most oil. I therefore provide means for guiding the burner in its up and down movements which means is associated with the pipe 10 95 depending from the burner bowl, as well as with the means for raising and lowering the burner, to be now described.

20 designates a bracket suitably fastened upon a front bar 20^a of the framework of 100 the stove. This bracket provides a support for an upright tubular stem 21 rigid with the top wall of the bracket. The latter is substantially in the form of an inverted U, with the front wall thereof closed and slotted, as at 22, to receive an indicator 23 fast upon the coupling member 16 and adapted to coact with suitable legends 24 provided on the front face of the wall to indicate the position of the burner.

The stem 21 may be made rigid with the bracket in any suitable way, and is of an internal diameter such as to receive slidably the stem 10. This stem 21 therefore 5 constitutes a guide for the stem 10.

Slidable upon the exterior of the stem 21 is a sleeve or collar 25. The sleeve has a rotatable but non-sliding connection with the upper end of the stem 10 which at the 10 point of its connection with the burner bowl is slightly enlarged as at 26. The means for effecting such connection may be of any suitable or preferred construction. Herein I have shown a collar 27 fast upon the stem 15 10 and a ring 28 fast upon the upper end of the sleeve and having inwardly projecting fingers 29 slidably engaging with the upper surface of the collar 27, said fingers being spaced from the upper end of the 20 sleeve a distance such as to provide grooves or notches for receiving the collar. It will be observed that when up and down movements are imparted to the sleeve 25, such movements will be transmitted to the stem 25 through this slidable connection.

The means for thus raising and lowering the sleeve preferably is of such construction as to render it possible to raise and lower the burner with substantial ease and speed, and yet is of an extremely simple 30 character. Thus it comprises a member 30 preferably semi-circular or arcuate in form which is mounted upon the bracket 20 as by means of arms 31 rigid with and depending from the opposite sides of the arcuate member. These arms are fastened to the opposite sides of the brackets as by means 35 of screws 32 which also serve to secure the bracket 20 in place upon the bar 20^a the 40 latter having apertured lugs 20^b for this purpose. Preferably these screws 32 are entered through slots 33 in the arms to enable the vertical adjustment of the member 30.

45 Rigid with the lower end of the sleeve 21 and extending radially therefrom is an operating rod 34 entered through a slot 35 in the member 30, and carrying a handle 36 at its free end. The slot 35 is approximately helical in shape, extending from one side of the member diagonally around the same to the opposite side thereof. Near its lower portion the inclination of the slot 50 is preferably somewhat less than in its upper portion, as indicated clearly at 37 in Fig. 3; and at its upper end the slot terminates in a short horizontal portion 38 in which the rod is adapted to engage to hold positively 55 the burner in its extreme elevated position. The shape of the slot is such that when the rod is at its lower extreme position the burner is in its lowermost position and hence the flame produced thereby is highest. 60 This is termed the lighting position. From this position the burner is gradually raised 65

to a medium or normally operative position which is reached when the rod is at the upper end of its lower inclined portion 37. In the movement of the rod from this latter position to its extreme upward position, the 70 burner is moved to the "out" position. These several positions, as illustrated in Fig. 1, are indicated by the pointer 23 coacting with the legends upon the front face of the bracket. 75

90 Preferably I provide means for retarding the movements of the rod with respect to the member, which means may comprise a bearing member 39 engaging with the inner wall of the member 30 (Fig. 5) adjacent the 80 edges of the slot therein. A spring 40 encircles the rod and bears between the sleeve and the bearing member serving to provide the necessary frictional engagement between the bearing member and the inner wall of 85 the member 30 to retard the movement of the rod in its slot. Thus by employing a spring of the proper strength the rod may be held thereby in any position in its slot. It will therefore be apparent that the use of 90 the upper horizontal portion 38 of the slot is not essential.

95 It will be seen that I have produced a raising and lowering means of a very practical character, which I have found to be efficient in operation in that it results in a substantial saving of time over the period of its use or life, and in that the amount of effort required is relatively small. At the same time the construction is extremely 100 simple so that it may be manufactured at a low cost.

I claim as my invention:

1. The combination of an oil receptacle, 105 and means for raising and lowering the receptacle including a pair of telescoping tubular members, a collar fixed upon one of said members, a sleeve loose upon the other member and slidably connected with said collar, and means for raising and lowering the sleeve comprising a stationary arcuate member having a slot therein and a rod rigid with the sleeve operating in said slot. 110

2. The combination of an oil receptacle, 115 means for raising and lowering the receptacle comprising a stationary arcuate member, a sleeve mounted for up and down movement and having a rotatable but non-sliding connection with the receptacle, the stationary member having a cam slot therein, and a rod rigid with the sleeve and operating in said slot. 120

3. The combination of an oil receptacle 125 having a tubular supply stem depending therefrom, a stationary upright stem providing a guide for said supply stem, a member longitudinally slidable upon the stationary stem and rotatably connected with said tubular stem, a stationary arcuate member having a cam slot therein, and a rod rigid 130

- with said rotary member and operating in said slot.
4. The combination of a stationary bracket, a tubular stem mounted on said bracket, 5 an oil supply stem movable through and guided by said tubular stem, an annular member longitudinally and rotatably slideable on said stem and having a rotatable but non-sliding connection with the supply 10 stem, and cam means for raising and lowering said annular member.
5. The combination of a stationary oil supply pipe, a vertically movable feed pipe, a flexible connection between the supply pipe 15 and the lower end of the feed pipe, and combined means for raising and lowering the feed pipe and guiding the same vertically in such movements comprising a stationary stem, an annular member slideable upon said 20 stem, cam means for raising and lowering said annular member, and means operatively connecting the annular member with said feed pipe.
6. The combination of a part movable vertically, a stationary guide stem for said part, 25 a member rotatable on said stem and rotatably connected with said part, a stationary member having a slot therein, a rod operating in said slot and rigid with said movable member, and spring means acting between 30 the movable member and the stationary member to retard the movements of said rod in its slot.
7. The combination of an oil burner, a stationary guide stem, a member rotatable on said stem and rotatably connected with the burner, a stationary member having a slot therein, a rod operating in said slot and rigid 35 with said movable member, a friction member slideable on said rod within the stationary
- member, and a spring acting between said friction member and the movable member whereby to retard the movements of the rod in said slot.
8. The combination of a stationary upright tubular stem, a sleeve rotatable on said stem, a pipe slideable in the stem and having a collar thereon, means on said sleeve providing a notch for receiving said collar, and cam means for raising and lowering the sleeve. 45
9. The combination of an upright stationary stem, a part guided for up and down movements in said stem and having a collar thereon, a pair of coaxial members one of 50 which is constructed to provide a notch adapted to be engaged by said collar and the other one of which has a cam slot therein, and a rod adapted to engage in said slot and connected with the member which engages the collar whereby to impart up and down movements to said part. 55
10. In an oil stove, the combination of an oil burner having a bowl mounted for up and down movement with respect to a constant level of oil, an oil supply pipe located rearwardly of the burner, means including a flexible tube connecting the burner with said supply pipe, a stationary upright member adapted to guide the burner for vertical movement, and means for raising and lowering the burner comprising a pair of members one of which is stationary and the other one of which is movable up and down and operatively connected with the burner, and cam means acting between said members. 60 65 70 75
- In testimony whereof, I have hereunto affixed my signature.

RUDOLPH HOFFMAN.
